UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 24, 1923. Serial No. 659,104.

My invention relates to railway traffic controlling apparatus, and particularly to apparatus of the type comprising means for supplying train governing energy to the trackway, and train carried governing means controlled by such energy.

More specifically the present invention relates to the trackway portion of such apparatus.

10 I will describe one form of apparatus embodying my invention, and will then point out the novel features thereof in claims.

15 In the accompanying drawings Fig. 1 (two sheets) is a diagrammatic view showing one form of apparatus embodying my invention.

20 Referring to the drawings, the reference characters 1 and 1^a designate the track rails of a railway track A over which traffic moves in both directions. These rails are divided by insulated joints 7 to form a plurality of track sections, of which only five sections 2—3, 3—3^a, 3^a—4, 4—5 and 5—6, are shown in the drawing.

25 Each track section is provided with a track circuit comprising a battery 8 connected across the rails adjacent one end of the section, and a track relay connected across the rails adjacent the other end and designated 30 by the reference character T with a distinguished exponent. In series with each battery 8 is the secondary of a transformer J, the purpose of which will be set forth hereinafter.

35 Westbound traffic along the track A is governed by signals S⁵ and S², whereas eastbound traffic is governed by signals S³ and S⁴. Each of these signals is adapted to give three different indications, such as "proceed", 40 "caution" and "stop", and as here shown, each signal is of the one arm, three position semaphore type.

45 Each signal is immediately controlled by a line relay designated by the reference character H with the same exponent as that applied to the signal. Each of these relays is of the polarized type, so that it is responsive to reversals of the polarity of the current by which it is energized. Referring particularly to signal S⁵, this signal is provided with a caution circuit which passes from battery B⁵, through wire 9, contact 10 of relay

H⁵, wire 11, operating mechanism of signal S⁵, wire 12, contact 13 of relay H⁵, and wire 14 to battery B⁵. This signal is also provided with a proceed circuit which passes from battery B⁵, through wire 9, contact 10; wire 16, polar contact 17 of relay H⁵, wire 18, operating mechanism of signal S⁵, wire 12, contact 13, and wire 14 to battery B⁵. 55 When relay H⁵ is energized by current of what I will term "normal" polarity, the neutral contacts 10 and 13 are closed and polar contact 17 is also closed, so that signal S⁵ indicates proceed. When relay H⁵ is energized with current of what I will term "reverse" polarity, contact 17 is open but the neutral contacts 10 and 13 are still closed, so that signal S⁵ then indicates caution. When relay H⁵ is de-energized, its neutral 60 contacts 10 and 13 are open, so that signal S⁵ then indicates stop.

65 Each of the remaining signals S², S³ and S⁴ is controlled in a similar manner by its associated line relay H, the proceed and caution circuits of these signals being omitted from the drawing, however, for the purpose of simplicity.

70 Line relay H⁶ for signal S⁵ is provided with a line circuit which passes from battery B², through pole-changer P², wire 19, contact 20 of track relay T², wire 21, contact 22^a of track relay T², wire 21^a, contact 22 of track relay T³, wires 23 and 24, contact 25 of track relay T⁴, wire 26, winding of relay H⁵, wires 27, 28 and 29, common wire O, wires 30, 31 and 32, and pole changer P² to battery B². Pole changer P² is operated by signal S² in such manner that when signal S² indicates proceed or caution, current of normal polarity is supplied to relay H⁵, so that signal S⁵ then indicates proceed; when, however, signal S² indicates stop, current of reverse polarity is supplied to relay H⁵, so that signal S⁵ then indicates caution. Of course, if any one of the track relays T², T³ or T⁴ is open, the circuit just traced for relay H⁵ is open, so that this relay is de-energized and signal S⁵ indicates stop.

80 Signal S² is controlled by relay H², which in turn is controlled by traffic conditions to the west of this signal through the medium of suitable apparatus which may, for example, be similar to the apparatus for the

control of line relay H^5 explained herein-after. Line relay H^5 , for eastbound signal S^3 , is provided with a line circuit which passes from battery B^4 through pole changer P^4 , wire 33, contact 34 of track relay T^4 , wire 35, contact 36 of a relay C^4 , wire 37, contact 37^a of track relay T^6 , wire 37^b, contact 38 of track relay T^2 , wire 39, winding of relay H^3 , wires 40, 31 and 30, common wire O , wire 41 and pole changer P^4 to battery B^4 . Pole changer P^4 is operated by signal S^4 , and in so far as this pole changer is concerned, the control of signal S^3 is the same as the control of signal S^5 explained hereinbefore. It will be noted, however, that the circuit for relay H^3 includes a contact 36 of a relay C^4 , so that signal S^3 will indicate stop whenever relay C^4 is de-energized.

Relay C^4 is provided with a circuit which passes from battery B^5 , through pole changer P^5 , wire 44, contact 45 of track relay T^5 , wire 46, contact 47 of track relay T^4 , wire 48, winding of relay C^4 , wires 49 and 41, common wire O , wires 29, 28 and 50 and pole changer P^5 to battery B^5 . It will be seen, therefore, that relay C^4 will be de-energized whenever track relay T^4 or T^5 is open, that is, whenever there is a train in section 4-5 or section 5-6. In other words, the line circuit for relay H^3 is directly controlled by the track relays for sections 2-3 and 3^a-4, and is indirectly controlled through the medium of relay C^4 by the track relays for sections 4-5 and 5-6, so that signal S^3 indicates stop whenever there is a train between points 2 and 6.

The line relay H^4 for signal S^4 is controlled by a circuit which is similar to the circuit hereinbefore traced for line relay H^5 . That is to say, relay H^4 is controlled by contact 42 of track relay T^4 , contact 43 of relay T^5 , and by other apparatus to the east of the stretch of track shown in the drawing.

Relay C^5 , corresponding to relay C^4 , is controlled in the same manner as relay C^4 , that is, the circuit for relay C^5 includes contact 52 of track relay T^4 and contact 51 of track relay T^5 , so that the westbound signal, located to the east of point 6, and corresponding to eastbound signal S^3 , is held in the stop position by a train between point 3^a and the signal in question.

The operation of the apparatus thus far described is as follows:

As a westbound train approaches the stretch of track shown in the drawing, it will first place signal S^4 at stop by operating the track relays to the east of point 6. As the train passes point 6 it will open track relay T^5 , thereby opening at contact 45 the circuit for relay C^4 , and the consequent opening of contact 46 of relay C^4 will open the circuit for line relay H^4 , thereby placing signal S^4 at stop. As the train

passes signal S^5 , it will place this signal at stop by opening track relay T^4 and thereby opening the circuit for line relay H^5 at contact 25. As the train passes signal S^2 it will place this signal at stop, so that signal S^5 will return to the caution position. When the train reaches such point to the west of signal S^2 this signal moves to the caution position, signal S^5 will return to the proceed position.

An eastbound train passing through this stretch of track places signal S^3 at stop as soon as it passes this signal, and it simultaneously will place signal S^5 at stop. When the train passes signal S^4 , this signal will, likewise, move to the stop position, while signal S^3 will remain in the stop position until the train passes point 6, that is, until relay C^4 is allowed to close.

In addition to the signaling system hereinbefore described, the apparatus shown in the accompanying drawing includes means for supplying train governing energy to the trackway. In the form here shown, this energy is alternating current, and is supplied to both rails of each section in such manner that under clear traffic conditions a source of alternating current is always connected across the rails in advance of a train. As here shown, each section is provided with two transformers, one adjacent each end of the section, which transformers are designated by the reference character J with distinguishing exponents. The secondary of each transformer is connected across the rails, whereas the primary of each transformer is at times supplied with alternating current, as will be explained hereinafter. Considering section 2-3, for example, transformer J^3 at the left hand end of this section is connected across the rails 1 and 1^a in multiple with relay T^2 , whereas transformer J^6 at the right hand end of this section is connected across the rails in series with the track battery 8. The transformers for each of the remaining sections are connected with the rails in similar manners.

Referring now to section 5-6, the transformer J^9 at the left hand end of this section is provided with a primary circuit which passes from the secondary of a transformer G^5 , through wire 72, back point of contact 73 of track relay T^5 , wire 74, primary of transformer J^9 , wires 75 and 76, front contact 77 of line relay H^5 , and wires 29 and 78 to transformer G^5 . This circuit is closed only when track relay T^5 is de-energized, and line relay H^5 is energized. It follows that when a westbound train enters section 5-6, it will receive train governing energy from transformer J^9 , provided that relay H^5 is energized, that is, provided that there is no train between point 5 and point 2.

The supply of train governing current to section 4-5 is controlled by two auxiliary relays D⁴ and D⁵, each of which is normally de-energized. Relay D⁴ is controlled by contact 54 of relay C⁴, the circuit for relay D⁴ being from battery B², through pole-changer P², wire 19, contact 20 of track relay T², wire 21, contact 22 of track relay T⁶, wire 21^a, contact 22 of track relay T³, wires 23 and 53, contact 54 of relay C⁴, wire 55, winding of relay D⁴, wires 56 and 41, common wire O, wires 30, 31 and 32, and pole-changer P² to battery B². It will be seen, therefore, that when relay C⁴ is de-energized, relay D⁴ is connected in the circuit of line relay H⁵ in multiple with the latter relay, so that relay D⁴ is then controlled in the same manner as relay H⁵ in so far as concerns track relays T², T⁶ and T³.

Relay D⁵ is controlled by a contact 57 of relay C⁵ in such manner that when relay C⁵ is de-energized relay D⁵ is connected in the line circuit of relay H⁴ in multiple with the latter relay.

The transformer J⁷ at the left hand end of section 4-5 is provided with a primary circuit which passes from the secondary of transformer G⁴, through wire 58, contact 79 of relay D⁴, wire 80, primary of transformer J⁷, and wires 81, 56, 41 and 65 to the secondary of transformer G⁴. This circuit is closed only when relay D⁴ is closed, and relay D⁴ is closed only when there is a train in section 4-5 or 5-6 and no train between points 2 and 4. It follows that a westbound train occupying section 4-5 will receive train governing energy provided that there is no other train between points 2 and 4.

Transformer J¹⁴ at the left hand section of 3^a-4 is provided with a primary circuit which passes from the secondary of transformer G³ through wire 82, front point of contact 83 of track relay T², wire 84, contact 85 of track relay T⁶, wire 86, primary of transformer J¹⁴, wire 87, common wire O and wires 30, 88 and 89 to the secondary of transformer G³. This circuit is closed only when track relays T² and T⁶ are closed, and so it follows that a westbound train occupying section 3^a-4 will receive train governing energy, provided that there is no other train between points 2 and 3^a.

Transformer J⁴ at the left hand end of section 3-3^a, is provided with a primary circuit which passes from the secondary of transformer G³, through wire 82, front point of contact 83 of track relay T², wires 84 and 90, primary of transformer J⁴, wires 91 and 92, contact 93 of line relay H², and wires 94 and 89 to the secondary of transformer G³. This circuit is closed only when track relay T² and line relay H² are closed, and so a westbound train occupying section

3-3^a will receive train governing energy provided there is no other train in section 2-3 or in the block to the west of signal S².

Transformer J³ at the left hand end of section 2-3 is provided with a primary circuit which passes from the secondary of transformer G³, through wire 82, back point of contact 83 of track relay T², wire 95, primary of transformer J³, wires 96 and 92, contact 93 of line relay H² and wires 94 and 89 to the secondary of transformer G³. This circuit is closed only when line relay H² is energized, so that a westbound train occupying section 2-3 will receive train governing energy provided there is no other train in the block to the west of signal S².

Considering the space between signals S² and S⁵ as a block, it will be noted that the supply of train governing energy to the two rear sections 3^a-4 and 4-5 is controlled only by traffic conditions within the block, that is, as far west as point 2, whereas the supply of train governing energy to the two forward sections 2-3 and 3-3^a is controlled by traffic conditions in advance of the block through the medium of line relay H². It is understood that point 3^a will be at least at maximum braking distance from point 2 for trains traveling at full speed.

Considering now an eastbound train, it will be noted that the primary circuit for transformer J⁶ at the right hand end of section 2-3 is controlled by a front contact 62 of track relay T⁶ and by a front contact 60 of track relay T³, so that the supply of train governing energy to section 2-3 is controlled only by traffic conditions between points 3 and 4. The transformer J¹³ for section 3-3^a is controlled by the back point of contact 62 of track relay T⁶, and the front point of contact 60 of track relay T³ and by contact 68 of line relay H⁴, so that the supply of train governing energy to section 3-3^a is determined by traffic conditions between points 3^a and 4, and also by traffic conditions in the block to the east of signal S⁴. The primary of transformer J⁵ for section 3^a-4 is controlled by the back point of contact 60 of track relay T³ and by contact 68 of line relay H⁴, so that the supply of train governing energy to this section is likewise controlled by traffic conditions in the block to the east of signal S⁴. The primary of transformer J⁸ is controlled by contact 97 of relay D⁵, so that the control of this transformer corresponds to the control of transformer J⁷ at the left hand of section 4-5. The primary circuit for transformer J¹² is controlled by apparatus to the east of the stretch of track shown in the drawing.

Considering the space between signals S³ and S⁴ as a block, it will be noted that supply of train governing energy to the two forward sections 3-3^a and 3^a-4 is controlled by traffic conditions in advance of

the block, whereas the supply of train governing energy to the rear section 2-3 is controlled only by traffic conditions within the block. It is understood, as before, that the distance from point 3 to point 4 is at least maximum braking distance for trains traveling at full speed.

It will be noted that the primary circuits for transformers J^3 , J^7 , J^9 , J^8 , J^5 and J^{13} are normally open, thereby economizing in the amount of train governing energy supplied to the track rails.

The primary circuit for each transformer J is supplied with current by a transformer G , and the primary of each transformer G is constantly connected with a transmission line M , which is supplied with alternating current by suitable means, such as a generator F .

It is understood that the apparatus shown herein is intended for co-operation with train carried governing mechanism, so arranged that when the train occupies a section which is supplied with train governing current in advance of the train, a proceed indication is given aboard the train, but that when the train occupies a section which is not supplied with train governing energy in advance of the train, a stop indication is given aboard the train.

I do not in the present application make any claim for the relay D^4 which is controlled by relay C^4 and in turn controls the supply of train governing energy to the rails of section 4-5 or for the corresponding relay D^5 which is controlled by relay C^5 , such invention being disclosed and claimed in my co-pending application, Serial No. 659,103 filed on the 24th day of

August, 1923.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track comprising a block made up of at least two track sections, means controlled only by traffic conditions in said block for supplying train governing current to the rear section, and means controlled by traffic conditions in advance of said block for supplying train governing current to the forward section.

2. In combination, a stretch of railway track comprising a block made up of at least three track sections, means controlled only by traffic conditions in the second and third sections for connecting a source of train governing current across the rails of the first section, and means controlled by

traffic conditions beyond said block for connecting sources of train governing current across the rails of the second and third sections.

3. In combination, a stretch of railway track comprising a block made up of two parts, means controlled only by traffic conditions in the forward part of said block for supplying train governing current to the rear part of the block, and means controlled by traffic conditions in advance of the block for supplying train governing current to the forward part of the block.

4. In combination, a stretch of railway track comprising a block, means controlled only by traffic conditions within said block for supplying train governing current to the block from the entrance end to a point at least at maximum braking distance from the exit end, and means controlled by traffic conditions in advance of said block for supplying train governing current from said point to the exit end of the block.

5. In combination, a stretch of railway track over which traffic moves in both directions, said stretch comprising a block made up of at least two track sections, means controlled by traffic conditions in the right hand section for supplying train governing current to the left hand section, means controlled by traffic conditions in the left hand section for supplying train governing current to the right hand section, means controlled by traffic conditions to the right of said block for supplying train governing current to the right hand section, and means controlled by traffic conditions to the left of said block for supplying train governing current to the left hand section.

6. In combination, a stretch of railway track over which traffic moves in both directions, said stretch comprising a block made up of at least two track sections, means controlled by traffic conditions in the right hand section for connecting a source of train governing current across the rails at the right hand end of the left hand section, means controlled by traffic conditions in the left hand section for connecting a source of train governing current across the rails at the left hand end of the right hand section, means controlled by traffic conditions to the right of said block for connecting a source of train governing current across the rails at the right hand end of the right hand section, and means controlled by traffic conditions to the left of said block for connecting the source of train governing current across the rails at the left hand end of the left hand section.

7. In combination, two sections of railway track, a track relay for the forward section, means including a front contact of said relay for supplying train governing current to the rear section, and means including a

back contact of said relay for supplying train governing current to the forward section.

8. In combination, three successive sections of railway track, track relays for the second and third sections, means controlled by a front contact of the relay for the second section and a front contact of the relay for the third section for supplying train governing current to the first section, and means controlled by a back contact of the relay for the second section and a front contact of the relay for the third section for supplying train governing current to the second section.

9. In combination, three successive sections of railway track, track relays for the second and third sections, means controlled by a front contact of the relay for the second section and a front contact of the relay for the third section for supplying train governing current to the first section, and means controlled by a front contact of the relay for the third section and by traffic conditions in advance of the third section for supplying train governing current to the second section.

10. In combination, three successive sections of railway track, track relays for the second and third sections, means controlled by a front contact of the relay for the second section and a front contact of the relay for the third section for supplying train governing current across the rails of the rear section, and means controlled by traffic conditions in advance of said block for connecting a source of train governing current across the rails of the forward section.

for the third section for supplying train governing current to the first section, and means controlled by a front contact of the relay for the third section and by traffic conditions in advance of the third section for supplying train governing current to the second section, and means controlled by traffic conditions in advance of the third section for supplying train governing current to the third section.

11. In combination, a stretch of railway track comprising a block made up of at least two track sections, means controlled only by traffic conditions in said block for connecting a source of train governing current across the rails of the rear section, and means controlled by traffic conditions in advance of said block for connecting a source of train governing current across the rails of the forward section.

12. In combination, a stretch of railway track comprising a block made up of two parts, means controlled only by traffic conditions in the forward part of said block for supplying train governing current across the rails of the rear part, and means controlled by traffic conditions in advance of said block for supplying train governing current across the rails of the forward part of the block.

In testimony whereof I affix my signature.

RONALD A. McCANN.
